United States Patent Office

Des. 197,313
Patented Jan. 7, 1964

197,313

FOOD CONTAINER

Herbert Jourdan Wanderer, 606 Cedar Ave.,
Elmhurst, Ill.

Filed Nov. 15, 1962, Ser. No. 72,506

Term of patent 3½ years

(Cl. D58—17)

FIG. 1 is an elevational view, partly in section of a food container, showing my new design;

FIG. 2 is a bottom plan view thereof;

FIG. 3 is a top perspective view thereof on a reduced scale;

FIG. 4 is an enlarged fragmentary sectional view of an upper portion of the container; and

FIG. 5 is an enlarged fragmentary sectional view of the bottom portion of the container.

I claim:

The ornamental design for a food container, as shown.
